RADIO ANTENNA CONTROLLING SYSTEM

Edward S. Peterson, Elmwood Park, Ill., assignor
to Automatic Electric Laboratories, Inc., a corporation of Delaware

Application October 30, 1942, Serial No. 463,981

8 Claims. (Cl. 250—33)

This invention relates in general to radio antenna controlling systems, and more particularly to novel arrangements for controlling and indicating the operation of aircraft antenna reels.

It is well known to employ a trailing wire antenna in aircraft and to provide, within the body of the craft, a reel or bobbin upon which the antenna is wound when it is not in use. Further, it is well known to unwind different amounts of the antenna at different times whereby to vary the length of antenna trailing the aircraft; since each frequency (or wavelength) of transmission has its own optimum antenna length, it will at once be apparent that this control over the length of the extended antenna affords a ready means for securing optimum performance of the antenna on whatever transmission frequency (or wavelength) is to be utilized in any given instance.

While an antenna reel may be provided with a hand crank to permit the pilot or radio operator to rotate it manually whenever he wishes to extend or retract the antenna, it is, for obvious reasons, highly desirable that he be relieved of this task and that the operation be made semi-automatic. Moreover, the advent of larger aircraft with increasingly complex controls frequently makes it desirable to place the reel at a considerable distance from the operator, in a part of the aircraft which is less congested than that in the immediate vicinity of the operator.

The primary object of the invention, therefore, is to provide a semi-automatic antenna reeling system wherein the reel itself is remote from the operator and wherein, for the sake of utmost flexibility of control, the operator is able to adjust the length of the trailing antenna with the same certainty and freedom as though he had a direct manual control over the reel. With this end in view, I have provided a semi-automatic, remotely controlled antenna reeling system wherein the reel's operation is at all times subject to the operator's will, giving him the power to start, stop or reverse its rotation whenever he desires, and wherein the operator is instantly apprised of every change made by the reel in the length of antenna extended.

A feature of the invention is the provision of a rotatable antenna reel having means for at all times indicating at a remote point the number of

turns of antenna unwound from said reel, this being accomplished without any form of mechanical link between the reel and the remote point, since such linkage would impose definite restrictions upon the location of the reel.

Another feature is the provision of an antenna reel and a remote indicator operated in synchronism with the reel without any mechanical linkage between the two.

10 A further feature is the provision of an antenna reel and a remote electric motor which is operated, under control of the reel, over electrical conductors interconnecting the two. Other features include the provision of means under control of the reel for causing said remote motor to operate in different directions at different times, the direction at each time depending upon the direction of the reel's rotation; the provision of means under control of the reel for starting and stopping said motor, as the reel itself starts and stops; and the provision of means under control of the reel mechanism for automatically disconnecting said remote motor from its source of current each time the antenna is completely retracted and thereafter reconnecting it just prior to a subsequent extension of the antenna, so that said motor will not be an undue drain on the aircraft's power supply during the long periods when the antenna is retracted.

20 30 A further feature is the provision of means for operating a remote electric motor by electrical impulses transmitted thereto under control of the antenna reel mechanism. Another feature is the transmission of said impulses over a plurality of circuits in a sequence depending upon the direction of rotation of the reel, the remote motor operating in a direction depending upon the sequence of said impulse transmission.

40 45 Still another feature is the provision of an antenna reel mechanism and a remote indicator which is controlled electrically by said mechanism, together with means local to said indicator for operating the same manually. Another feature is the provision of an arrangement for normally maintaining said manual operating means disengaged from said indicator and engaging it therewith only when it is desired to operate said indicator by hand.

50 A further feature is the provision of a reel

mechanism which ordinarily is controlled remotely, but which has an arrangement for controlling its own operation under certain abnormal conditions, said arrangement having means for insuring such self control even when a transient condition simulating the normal operation of the reel arises in the course of the abnormal condition. Another feature is the use of a slow relay whose delayed operation bridges the period of the transient condition and absorbs its effect.

Further features and objects of the invention will be apparent from the following description of one embodiment thereof, reference being made to the accompanying drawings, in which

Fig. 1 is a front elevation of the control unit for the reel, showing the cable connected thereto,

Fig. 2 is a side elevation of the control unit with the cable disconnected,

Fig. 3 is a perspective view of the box which covers the rear of the control unit.

Fig. 4 is a front elevation of the reel and its driving unit, showing the cables connected thereto,

Fig. 5 is a top elevation of the reel and its driving unit,

Fig. 6 is an end elevation of the reel and its driving unit, as seen when viewed from the left side of Figs. 4 and 5, the cables having been detached from said driving unit,

Fig. 7 is an enlarged back view of the control unit illustrated in the Figs. 1, 2 and 3, with the back cover removed to show the mechanism contained therein,

Fig. 8 is a sectional view taken along the line 8-8 of Fig. 7,

Fig. 9 is a sectional view taken along the line 9-9 of Fig. 7, certain parts having been omitted for the sake of clarity,

Fig. 10 is a side elevation of the control unit, as seen when viewed from the right-hand side of Fig. 7, certain parts having been omitted in the interest of clarity,

Fig. 11 is an enlarged top view of the driving unit for the reel, with the top cover removed and with part of the motor casing cut away to show, in cross section, the clutch mechanism.

Fig. 12 is a front view of the driving unit, without its motor and with the front cover removed to show the contactor and limit springs,

Fig. 13 is a sectional view taken along the line 13-13 of Fig. 11, the motor being omitted,

Fig. 14 is a perspective view of the contactor.

Fig. 15 is an enlarged longitudinal section of the worm and limit disc assembly illustrated in Figs. 11 and 13, and

Fig. 16 is a schematic diagram of the apparatus illustrated in the above figures together with the electrical circuits comprising the control system therefor.

The apparatus disclosed in the drawings is divided into two electrically interconnected units, and before explaining their interdependent operation as components of a single system, the mechanism of each unit will be described separately.

The control unit (Figs. 1, 2, 3, 7, 8, 9 and 10)

The control unit is housed within a generally rectangular box 20 having cover 21, and should be positioned in the aircraft within the sight and reach of the pilot or radio operator. It may be mounted upon any suitable support by means of the screws 22 which pass through the holes in the back of the box, the cover thereafter being

attached to the front of the box by the screws 23 which pass through the face of the cover into tapped holes 24 in the corners of said box. The outer edges of the cover are bent over at right angles to the face, giving the cover rigidity and forming a continuous peripheral lip 25 slightly overlaying the walls of the box when the cover is in place. This lip is comparatively narrow at the top of the box but grows wider near the bottom as shown in Figs. 2 and 10, being wide enough across the bottom of the box to permit a receptacle or jack 26 to be mounted therein. When the cover is in place, the upper part of this receptacle fits into a wide slot 29 provided in the bottom wall of box 20. All electrical connections to the control unit are made over a ten conductor cable 27 having a plug 28 which is insertable into said receptacle or jack.

Mounted on the inside face of the cover by means of two L-shaped brackets 30 and 31, is a three-gang motor of the type disclosed in my copending application Serial No. 450,102, filed July 8, 1942. This motor has three generally U-shaped stator pole pieces 32, 33, and 34 spaced apart one above another. They are supported thus by a pair of vertical rods 35 and 36 passing through holes in the brackets 30 and 31, through corresponding holes in the free ends of each pole piece and through spacing sleeves such as 37. Nuts at both ends of each rod securely clamp the stator pole pieces between said brackets, forming a rigid field structure. The pole pieces are of soft iron or other magnetic material, and each has a magnetizing coil (38, 39, 40) wound around its center section.

Parallel to the rods 35, 36 and centrally disposed between the ends of the pole pieces is a rotatable shaft 41 supported at both ends by self-aligning bearings such as 42. The top bearing is seated in a concave socket stamped in the bracket 30, and is held there by a resilient retaining plate 43, similarly stamped, which is secured to the rods 35, 36 by nuts. The lower bearing is held in like manner between the bracket 31 and a resilient retaining plate 44.

Three rotor elements 45, 46, and 47 are rigidly fastened to the shaft 41, each lying in the space between the open ends of one of the pole pieces. Like the pole pieces, these rotor elements are of soft iron or other suitable magnetic material, and as best seen in Fig. 16 they are staggered at angles of 60° from each other.

Linked to the shaft 41 by means of a worm 48 and a gear 49 is a counter 50 of the Veede type. This is secured by screws to the inside of the cover of the control box, its registration being visible from outside the box through a window 51. The ratio of the worm-to-gear linkage just mentioned preferably is such that the counter will read directly in terms of revolutions of the shaft 41; in other words the total registration visible through window 51 should increase one unit for each revolution of the motor shaft in one direction and should decrease one unit for each revolution of said shaft in other direction. Manual adjustment of the registration may be made by means of a reset knob 52 which is fastened to a short shaft passing through the front cover of the control box. Normally, as seen in Fig. 9, a helical spring 54 urges this knob outwardly from the cover; therefore the disc 55 which is fastened to the same shaft ordinarily is not in contact with the rubber disc 56 secured to the shaft 41 of the motor. By manually de-

pressing the reset knob against the force of spring 54 the outer edge of disc 55 will be brought into engagement with the periphery of the rubber disc, and if the knob then is rotated while thus depressed the disc 55 will rotate the shaft 41 through its frictional engagement with the rubber disc, causing the counter reading to be changed accordingly.

A tell-tale lamp assembly 57 of well-known type is mounted in the lower corner of the cover. This has a miniature incandescent lamp 58 suitably supported in a socket 59 and is clearly visible from the front of control box when lighted. Also mounted on the inside of the cover is a three position rotary switch 60, which may, for example, be of the same general type as disclosed in United States Patent No. 2,226,719, granted December 31, 1940, to A. Hall. The shaft of this switch protrudes through a hole in the cover, and secured thereto is a manual operating lever 62, by means of which it may be rotated in either direction from its normal position (Fig. 1) in order to operate certain electrical contacts as will be explained more in detail presently. When the switch is displaced either to its "in" position or to its "out" position a spring member 53, fastened to the switch shaft, will maintain it in that position until it is manually restored to its normal, or "off," position.

On an L-shaped bracket 63 which is attached by screws to the inside of the cover there is mounted a horizontal relay of the telephone type. This relay has a core 64, an L-shaped heel piece 65, and an L-shaped armature 66, all of magnetic material. The core is fixed rigidly to one end of the heel piece and the armature is pivoted on a knife edge 67 at the other end of the heel piece. Around the free end of the core is wound a coil 68 which when energized attracts the armature 66, thereby opening an electrical contact 69 mounted on the heel piece. A heavy copper collar, or slug, 70 is mounted on the core adjacent to the winding 68 which, as is well known, makes the relay slow-to-release (i. e., delays the restoration of the armature to normal upon deenergization of the winding).

Since the entire mechanism of the control unit is mounted on the cover 21 as explained above it may easily be removed for inspection, adjustment, or repair simply by removing the screws 23 which hold the cover in place, and it may be disconnected from the driving unit simply by removing the plug 28 from the jack 26.

The driving unit (Figs. 4, 5, 6, 11, 12, 13, 14 and 15)

The antenna reel 71 is rotatably mounted on a spindle affixed to the channel-shaped member 72. The latter member may be positioned anywhere in the aircraft without regard to the location of the control unit, and hence should be so situated within the available space as to achieve the most efficient operation of the antenna that is possible. The reel is provided with an emergency hand crank 73 by means of which it may be rotated manually in the event that the driving unit should for any reason become inoperative.

Also secured by screws to the member 72 is the casing 74 of the driving unit. This casing is subdivided into four compartments 75, 76, 77 and 78, three of which are separated from one another by a pair of vertical partitions 79 and 80, the fourth (compartment 78) being separated from the first two but communicating with the

third (compartment 77). Access may be had to compartments 75 and 76 by removing a cover 81 which is attached by screws to the top of casing 74. Access may be had to compartments 77 and 78 by removing a cover 82 which is attached by screws to the front side of casing 74.

Within compartment 77 is a flat plate 83 mounted on the partition 80 by means of screws. A portion 84 of this plate is bent outwardly at right angles to the remainder and forms a support for a pair of electrical contacts 85 and 86. Also within the same compartment is an electrical contactor 87 which is controlled by a disc-shaped cam 88 securely fastened to one end of the rotatable shaft 89. This cam is made of insulating material.

Three electrical contacts 90, 91 and 92 are mounted in operative relationship with cam 88, supported on appropriate insulators 93 which are positioned at equal intervals around a circle concentric with said cam. Each of the contacts comprises a pair of superposed springs spaced apart at one end by an insulator 94. The three bottom springs (i. e., those which are mounted nearest the partition 80) are arcuate in shape; each of the top springs has a corresponding arcuate portion and, at its free end, a radial portion 95 which extends inwardly to a point underneath cam 88 where it is embossed to present a generally dome-shaped surface to the cam. The latter springs are tensioned toward the cam so that the boss on each spring engages the underneath face of said cam. This face is divided into two segments 96 and 97, one raised and the other recessed. As the cam is rotated, the raised segment 96 depresses each top spring in turn, maintaining it depressed until the rotation of the cam brings the recessed segment 97 over the radial portion of that spring, whereupon the spring restores due to its own tension. During the period that it is thus depressed, each top spring engages its associated bottom spring. Preferably, one or both springs will be provided with a small, precious-metal contact at the point of engagement. It will be seen that during rotation of the cam the three contacts 90, 91 and 92 are closed in sequence and that each, when closed, remains closed while the cam rotates through an angle of approximately 200°. This angle may be altered, of course, by changing the proportions of the two segments of the cam, but 200° has been found to give very satisfactory performance.

A pair of receptacles or jacks 98 and 99 are mounted in one wall of a compartment 78. All electrical connections to the driving unit are made over two cables: the ten-conductor cable 71 which has a plug 100 insertable into jack 98 and a battery cable 101 which has a similar plug 102 insertable into jack 99. The wiring between the jacks and the various contact springs in compartment 77 has been omitted from Fig. 12 for the sake of clarity but it will be appreciated that the electrical connections conform with the circuits shown in Fig. 16.

Secured to the one end of the casing 74 by means of screws is a reversible, series-wound, direct current motor 102 which has a built-in electromagnetic clutch, as shown in cross-section in Fig. 11. The driving element 103 of the clutch is firmly attached to the shaft 104 of the motor, and supports a ring 105 of non-magnetic friction material. This ring has one face conforming with the cone-shaped portion of the driven

element 108. The latter element is free to slide axially on the shaft 109, but a pin 110 extending through shaft 109 and having its ends in appropriate slots or keyways in the driven element prevents any rotary displacement between the two. The driving element, the driven element, and the casing of the motor are all formed of suitable magnetic material. Within said casing is mounted a coil 111 which when energized attracts the driven element 108 toward the driving element 103, the principal path of the flux being indicated in Fig. 11 by the heavy dotted line. This causes the driven element to slide along the shaft 109 against the force of the light spring 112 until the conical portion thereof engages the ring 105. While thus engaged any rotation of the motor shaft 104 will drive the element 108 and hence produce a corresponding rotation of the shaft 109. Upon deenergization of the coil 111, the spring 112 forces the driven element away from the driving element and brings the conical portion into engagement with the face of the stationary braking member 113. This quickly halts the rotation of the shaft 109.

The rotation of shaft 109 which occurs when the clutch is "engaged" and the motor is running is communicated to the shaft 114 by a pair of spur gears 115 and 116 securely fastened to the respective shafts. A key 117 in shaft 114 causes the worm 118 to turn with said shaft, and this (through the worm wheel 119) rotates the shaft 89. As previously pointed out, cam 88 is firmly attached to one end of the shaft 89. A chain drive 120 having a sprocket at the other end of shaft 89 links said shaft with the antenna reel 71, the ratio of the sprockets being such that two revolutions of shaft 89 will cause but a single revolution of the reel.

It should be noted that the key 117 in keyway 121 of the worm 118 (see Fig. 15) permits said worm to slide in an endwise direction on the shaft 114 although preventing any rotary displacement between the two. On one end of the worm and integral therewith is a disc 122 which hereinafter will be referred to as the "out limit" disc. A second disc 123 which will be called the "in limit" disc is slidably mounted on shaft 114 adjacent to the same end of said worm. The helical spring 124 urges the "in limit" disc to the left, normally holding its collar against the end of key 117 as shown in Fig. 15; a lighter helical spring 125 between the "in limit" disc and worm 118 urges the worm to the left. Movement of the worm to the left, however, ordinarily is opposed by a force resulting from the weight of the "fish" 126 attached to the end of the antenna 127. Assume, for example, that the antenna is partially reeled out. Due to the weight of the "fish" (plus, of course, the weight of the extended portion of the antenna) there is a tangential pull on the reel tending to rotate the reel (and hence shaft 89) in a clockwise direction. It will be seen from Fig. 13 that, because of this tendency, the worm wheel 119 urges the worm to slide to the right along shaft 114. This force is sufficient to overcome the light spring 125, thereby bringing the "out limit" disc into engagement with the "in limit" disc, but is not great enough to overcome spring 124, since the initial compressive strength of the latter spring is greater than the force produced by the rotational pull of the antenna. Accordingly spring 124 maintains the "in limit" disc where it is shown in Figs. 11 and 13, this being the position in which its collar is in

contact with the key 117 as shown in Fig. 15.

Under special circumstances which will be set forth more in detail presently, the worm will slide along shaft 114, either in one direction or the other from the position in which it is shown in Figs. 11 and 13. When it slides to the left (such movement being limited by the collar of spur gear 116 which acts as a stop) the "out limit" disc engages a bushing on the lever 129 urging it to the left. This makes the shaft 130 to which the lever 129 is rigidly fixed rotate in a clockwise direction, whereupon the arm 131, also fixed to said shaft, rotates in the same direction, causing the electrical contact 85 to close. A second lever 133 similar to the one just described has its shaft 134 passing through the partition 89 adjacent to shaft 130 of the first lever. When the worm 118 slides to the right along shaft 114 it displaces the "in limit" disc against the force of spring 124 until said disc is stopped by sleeve 135. On such movement, the "in limit" disc engages a bushing on lever 133, rotating this in a counterclockwise direction and hence causing the arm 137 to open electrical contact 86.

Mode of operation (outline)

Having described in detail the structure of the control unit and of the driving unit for the reel, the manner of their operation will now be explained briefly, attention being directed particularly to Figs. 1 and 4.

It will be assumed that an aircraft equipped with the two units is in flight and that the pilot or radio operator wishes to extend the antenna. To do this, he throws the switch lever 62 to its "out" position, which immediately operates the magnetic clutch associated with motor 102 and causes said motor to begin to turn the reel 71 in a clockwise direction to unreel the antenna. At substantially the same time, the driving mechanism also causes the tell-tale lamp 57 in the control unit to light, thereby indicating to the operator that unreeling has begun. As unreeling progresses, the contactor 87 in the driving unit transmits electrical impulses to the three-gang motor in the control unit, causing the latter to operate the Veeder counter in such a way that, for each revolution of the reel, the counter will add one unit to the reading visible through window 51. At the start of unreeling, this reading is "000," and hence at every instant thereafter it will show the exact number of turns of antenna which have been unreeled.

As already indicated, the optimum performance of the aircraft's antenna system will occur on a wavelength which is proportional to the length of antenna trailing the aircraft; therefore it is self-evident that the operator ordinarily will not wish to extend the whole antenna, but only a certain length, that length being the one whose operation is optimum on the wavelength which he intends to use for radio communication on this particular occasion. Knowing how much antenna he wants extended, the operator will watch the dials on the Veeder counter as the driving mechanism pays out the antenna, and when the counter indicates that the desired number of turns have been unreeled, he will bring the mechanism to a halt by restoring the switch lever 62 to its "off" position. This manual operation stops the motor 102, releases the magnetic clutch and causes the three-gang motor to stop operating the Veeder counter; it has, however, no effect upon the lamp 57 which therefore remains lighted as a positive reminder to

the operator that a portion of the antenna is extended.

While the antenna is thus extended it may be used in the conventional way for radio communication, it being assumed that the aircraft's radio transmitter is coupled to the antenna in some suitable manner, such as, for example, via a connection (shown dotted in Fig. 4) to the small metallic trolley wheel which engages the antenna at a point intermediate the reel and the fairlead.

Assuming now that the operator has finished the radio communication for which he extended the antenna, he will throw the switch lever 62 to its "in" position to retract the antenna once more. This again operates the magnetic clutch and initiates the operation of motor 102, the latter now rotating in such a direction as to turn the reel 71 in a counterclockwise direction. Contactor 87 again transmits electrical impulses to the three-gang motor in the control unit causing this motor to rotate the shaft of the Veeder counter in the reverse direction, whereby the counter subtracts one unit from its reading for each revolution of the reel as the antenna is reeled in. When the "fish" 126 at least enters the mouth of the fairlead, the driving mechanism automatically stops itself, halts the operation of the Veeder counter (which now will have been restored to normal, i. e., its "000" position) and causes the lamp 57 to be extinguished.

Although ordinarily operating in the above way, the driving mechanism can, under certain abnormal conditions, refuse to unreel the antenna even though the switch lever 62 is thrown to its "out" position. These guarding arrangements will be made clear presently.

Detailed operation (reeling out the antenna)

For 16 shows the electrical circuits interconnecting the above described units. Essential parts of the mechanism are also shown schematically, each in the position normally occupied by that part when the antenna is fully retracted. It will be noted that under such circumstances the worm 118 and the two limit discs are displaced to the right of the position in which they were shown in Figs. 11 and 13, whereby the "in limit" disc 123, by operating lever 133, maintains contact 86 open. Spring 124 is compressed by this displacement, but it is unable to force the displaced members to the left on shaft 114 because to do so it would have to rotate worm wheel 119 in a counterclockwise direction, such rotation being prevented by the fact that the "fish" 126 is already pulled into the fairlead as far as it will go and will not permit the reel (hence the worm wheel) to turn further in said counterclockwise direction.

In order to reel the antenna out, the operator throws switch 60 to its "out" position and leaves it there, as already indicated. This switch at contact 140 thereupon closes the following circuit for operating the motor 102 in the direction indicated by arrow A: positive battery, conductor 141, contacts 140 and 69, resistor 142, conductor 143, winding 144, motor 102, and negative battery. At the same time the clutch is operated over the following circuit: positive battery, conductor 141, contacts 140, 69, and 145, conductor 146, winding 111, and negative battery. With the clutch operated and the motor turning in the direction indicated by arrow A the gear 115 begins to rotate with its top coming toward the observer. Accordingly the gear 116 (and hence the worm

118) rotates with its top going away from the observer.

When the worm rotates in this direction, it necessarily follows that one of two things must happen: Either the worm will begin to screw itself to the left on shaft 114 (assuming that the worm wheel 119 remains stationary and acts as a rack for the worm) or else the worm wheel 119 will begin to turn in a clockwise direction (assuming that the rotating worm remains in its original position on shaft 114). Were it not for spring 124 urging the worm to the left it is clear that the latter would happen, for the antenna's tangential pull on the reel due to the weight of "fish" 126 tends to rotate the worm wheel in a clockwise direction and, at the same time, tends to hold the rotating worm in its original position on shaft 114. However, as already pointed out the compressive strength of spring 124 which urges the worm to the left is greater than the force resulting from the rotational pull of the antenna which urges the worm to the right; accordingly, upon commencing to rotate, the worm at once begins to screw itself to the left along shaft 114 under the influence of spring 124. This spring obviously will keep the "in limit" disc 123 in contact with the "out limit" disc 122 as it moves to the left and, through worm 118, it also exerts on the worm wheel sufficient force to prevent the latter from rotating in a clockwise direction.

The movement of the members along shaft 114 continues until the worm and the two discs reach the position in which they are shown in Figs. 11 and 13. At that time the collar on the "in limit" disc 123 comes into contact with the key 117 (see Fig. 15) which prevents the spring 124 from urging the members further to the left. Being no longer overpowered by the pressure of the spring 124, the rotational pull of the antenna now becomes effective to start the reel and worm wheel 119 turning in a clockwise direction, as they would have done at the outset except for the presence of said spring. It should be understood that the "fish" 126 is sufficiently heavy to turn the reel and the worm wheel at as high a speed as the rotating worm will permit. In effect, then, the weighted antenna unreels itself, the worm functioning as a motor-driven governor or escapement which merely controls the speed at which such unreeling takes place. The tangential pull of the antenna on the reel is, of course, present throughout the whole time that the antenna is unreeling, and it is this force, transmitted to the worm through worm wheel 119, which urges the worm to the right, maintaining the "out limit" disc in contact with the "in limit" disc as seen in Figs. 11 and 13.

It will be appreciated that the mass of the reel 11 and of the antenna wound thereon is so distributed as to give the reel considerable inertia, and that, accordingly, an appreciable interval will elapse before the "fish" 126 can accelerate the reel from a state of rest to its full speed. At the beginning of this brief interval the rotating worm will continue to screw itself to the left along shaft 114, but as the reel gains speed the worm will be returned to the right until it finally reaches the position shown in Figs. 11 and 13, where it remains throughout the balance of the unreeling process, as indicated above. This slight axial movement of the worm during the period that the reel is accelerating represents a transient condition which, if not carefully controlled, is capable of bringing about a highly un-

desirable result. If, for example, the worm moves to the extreme left on shaft 114, the "out limit" disc 122 will rotate the lever 129, close contact 85, and at once halt the mechanism by operating relay 68, as will be made clearer from the ensuing description. To prevent such action, the resistor 142 is included in the circuit for motor 102 for the purpose of limiting the motor's starting torque; this insures that the shaft 114 will not reach an excessive speed before the rotation of reel 71 is initiated, and hence limits the distance which the worm will move to the left during this transient period, thereby preventing the "out limit" disc from closing contact 85.

Returning now to the initial axial movement of the worm and limit discs (i. e., that movement which takes place before the antenna begins to unreel) it will be seen that when the "in limit" disc moves to the left it causes the lever 133 to rotate in a clockwise direction, closing contact 86. This contact completes the following circuit: positive battery, contact 86, conductor 147, lamp 58, conductor 148, and negative battery, thereby lighting lamp 58 in the control unit to indicate that the driving unit has started to operate as a result of the operation of switch 60. The closing of contact 86 also completes preenergizing circuits for the field coils 38, 39 and 40 of the three-gang motor. The preenergizing circuit for winding 38 extends from positive battery over contact 86, conductor 147, winding 38, resistor 149, conductor 148, to negative battery. Similar circuits for windings 39 and 40 extend over the resistors 150 and 151 respectively. It should be noted, however, that resistor 151 is short-circuited over a path which may be traced from negative battery, via conductor 148, resistor 151, conductor 153, contact 90 of the contractor (this being shown schematically in Fig. 16 as a metallic cam 88 having an insert 152 of insulating material), back to negative battery; accordingly the motor winding 40 is connected directly to the battery in the following circuit: positive battery contact 86, conductor 147, winding 40, conductor 153, contact 90, and negative battery.

The resistors 149 and 150 in series with windings 38 and 39, respectively, maintain the current flowing through these windings at a low value, whereby the stator pole pieces 32 and 33 are magnetized only slightly. The pole piece 34 on the other hand is strongly magnetized, since there is no resistance in series with winding 40; but, because the rotor element 47 is already positioned directly across the open ends of this pole piece, there is no tendency for the shaft 41 to rotate.

With the windings of the three-gang motor thus energized as a result of the "in limit" disc moving to the left and closing contact 86, the worm wheel 119 now begins to turn in a clockwise direction under control of the rotating worm as already explained, and hence the antenna begins to unreel. Cam 88, driven by the worm wheel, also begins to turn in a clockwise direction and soon causes contact 91 to short-circuit resistor 149. Therefore the motor winding 38 is connected directly to the battery in the following circuit: positive battery, contact 86, conductor 147, winding 38, conductor 154, contact 91, and negative battery. This obviously increases the flow of current through winding 38, and consequently the pole piece 32 (now strongly magnetized) attracts the rotor element 45 turning the shaft 41 in a clockwise direction. Were it not for the fact that the pole piece 34 is also strongly magnetized at this time, it is apparent that the shaft would be

rotated 60° from its initial position (i. e., the amount which would align the rotor element 45 directly across the open ends of the pole piece 32); actually, however, the shaft will not rotate more than 30° because the attraction of the rotor elements 45 and 47 by their respective pole pieces becomes equal at that point.

As cam 88 continues to rotate, it next opens the circuit extending over contact 90, whereby the motor winding 40 is now energized only by current reaching it over its preenergizing circuit which includes the resistor 151. The resultant drop in the magnetization of pole piece 34 permits the shaft 41 to rotate an additional 30° in a clockwise direction under the influence of pole piece 32 which still is strongly magnetized. Rotor element 45 now is aligned directly across the ends of pole piece 32, and it will be clear that shaft 41 has rotated a total of 60°.

While it has been indicated that this rotation takes place in two equal steps, it should be mentioned that in actual practice the first step may be slightly less than 30° and the second step slightly more. The exact point at which the 60° rotation is divided will depend somewhat upon the magnitude of the load on the three-gang motor, and therefore varies slightly with changes in the viscosity of the bearing lubricant at different altitudes. Since the dividing point in all cases approximates a 30° rotation very closely, no error will result if it is assumed, for the purpose of this description, that in the above case and all similar cases the two steps which make up the 60° rotation are equal.

As cam 88 continues to rotate it next causes contact 92 to short-circuit the resistor 150 whereby the motor winding 39 is connected directly to battery over following circuit: positive battery, contact 86, conductor 147, winding 39, conductor 155, contact 92 and negative battery. Consequently pole piece 33 becomes strongly magnetized and attracts the rotor element 46; this tends to turn the shaft 41 through an additional 60° in a clockwise direction but because the pole piece 32 still is strongly magnetized at this time the rotation again is limited to 30° as explained before. Next, the rotating cam 88 opens the circuit extending over contact 91, thereby causing the motor winding 38 to be energized only by current reaching it over its preenergizing circuit. Since pole piece 33 now is the only one strongly magnetized, it is able to rotate the shaft an additional 30° bringing the rotor element 46 directly across the open ends of that pole piece.

Shaft 41 now has rotated a total of 120°. From the preceding description it will be clear that the cam 88, by continuing to turn in a clockwise direction under the influence of the worm wheel 119 as the antenna unreels, next will short-circuit resistor 151 over contact 90 (thereby causing the pole piece 40 to be strongly magnetized) and then will interrupt the short-circuit of resistor 150 which extends over contact 92 (thereby reducing the magnetization of pole piece 39). At each of these times the shaft 41 will be turned an additional 30° in a clockwise direction.

While rotation of shaft 41 thus takes place in increments of 30°, it should not be assumed that the shaft comes to a complete stop after each 30° rotation; actually the field windings 38, 39 and 40 are energized in such rapid sequence that the momentum of the rotating system of the three-gang tends to sustain the shaft's movement between successive 30° steps. This, together with

the fact that the field windings are never completely deenergized, makes the motor's operation considerably smoother than would otherwise be the case.

As long as the antenna continues to unreel, the three-gang motor will continue to operate in the manner described; its mode of operation will be made somewhat clearer by reference to the following table which shows the status of the field coils and shaft of the three-gang motor at the end of each successive 60° rotation of the cam 88 throughout the first three complete revolutions of said cam:

Position of cam 88 relative to its Fig. 16 position	Field coils which are completely energized	Position of shaft 41 relative to its Fig. 16 position
0°		0°
60° clockwise	38 and 40	30° clockwise
120° clockwise	38	60° clockwise
180° clockwise	38 and 39	90° clockwise
240° clockwise	39	120° clockwise
300° clockwise	39 and 40	150° clockwise
360° clockwise	40	180° clockwise
420° clockwise	38 and 40	210° clockwise
480° clockwise	38	240° clockwise
540° clockwise	38 and 39	270° clockwise
600° clockwise	39	300° clockwise
660° clockwise	39 and 40	330° clockwise
720° clockwise	40	360° clockwise
780° clockwise	38 and 40	390° clockwise
840° clockwise	38	420° clockwise
900° clockwise	38 and 39	450° clockwise
960° clockwise	39	480° clockwise
1,020° clockwise	39 and 40	510° clockwise
1,080° clockwise	40	540° clockwise

It will be noted from the above that each 120° rotation of cam 88 causes the shaft 41 of the three-gang motor to rotate through 60° . If the cam turns through 240° , shaft 41 will turn 120° ; if the cam turns 360° , the shaft will turn 180° ; and so on, the ratio of the angle of the cam's rotation to that of the shaft always being 2:1.

As the antenna unreels, each revolution of reel 71 produces two revolutions of the worm wheel 119 and hence two revolutions of cam 88. Cam 88 by its two revolutions produces one revolution of the shaft 41. Therefore it will be apparent that for every revolution of the reel in a clockwise direction there is a corresponding revolution of the shaft 41 in a clockwise direction. The counter 50, driven by the shaft 41, registers each revolution taken by the latter and hence in effect, registers each revolution taken by the reel. If its reading was "000" at the time rotation of the reel began, the reading will be "001" at the end of the first revolution of the reel, "002" at the end of the second, etc., at every instant indicating the exact total number of revolutions which the reel has made.

With this indication as a guide, the operator may stop the reeling out process at any desired point. To do this he simply observes the counter reading as unreeling progresses, and, when the counter indicates that the desired number of turns of antenna have been unwound, he restores the switch 60 to normal, thereby opening the circuit of motor 102 at contact 140 and opening the circuit of the clutch magnet 111 at contacts 140 and 145. Although the motor 102 may coast for a short interval after its circuit is interrupted, the rotation of shaft 114 is quickly halted due to the driven element of the clutch engaging the braking member 113 as already explained. This, of course, stops the rotation of worm 118, so that the worm wheel 119 (and hence the reel 71) can turn no further. Cam 88 also ceases to rotate, halting the shaft 41 of the three-gang

motor in a position corresponding to the position in which the reel was stopped, whereby the operation of counter 50 stops with an exact registration of the total number of turns of antenna which have been unreeled. All movable parts now are motionless, the two limit discs remaining in the position shown in Figs. 11 and 13, and lamp 58 remaining lighted as an additional reminder that a portion of the antenna is extended.

10

Detailed operation (reeling the antenna in)

When the operator is ready to reel the antenna in, he throws switch 60 to its "in" position and leaves it there. This at contact 156 completes

15

the following circuit for operating motor 102 in the direction indicated by arrow B: positive battery, contact 86, conductor 147, contact 156, conductor 157, field winding 158, motor 102, and negative battery. At the same time, the following circuit is completed for operating the magnetic clutch: positive battery, contact 86, conductor 147, contact 159, winding 111, and negative battery. With the clutch operated and motor 102 turning in the direction indicated by

20

arrow B, gear 115 begins to rotate with its top going away from the observer. Accordingly, gear 116 (and hence worm 118) begins to rotate with its top coming toward the observer. When this happens it is obvious that either the worm must

25

screw itself to the right along shaft 114 (assuming that worm wheel 119 remains stationary) or the worm wheel 119 must begin to turn in a counterclockwise direction (assuming that worm remains in its initial position on shaft 114). Here again, the compressive strength of spring 124 is sufficient to prevent the worm from moving to the right along shaft 114 (although the drag of the antenna manifestly urges it to do so), and therefore the rotating worm begins to turn the worm

30

wheel 119 in a counterclockwise direction. This causes the cam 88 to turn in the same direction, and causes the reel to commence winding up the antenna.

35

Assuming that the counterclockwise rotation of cam 88 starts from the position in which said cam is shown in Fig. 16, it will be seen that, at the start, resistor 151 is short-circuited, while resistors 149 and 150 are not; accordingly, pole piece 34 of the three-gang motor is the only one

40

strongly magnetized. As cam 88 turns, it first causes contact 92 to short-circuit resistor 158, thereby strongly magnetizing the stator pole piece 33, whereupon the resultant attraction of rotor element 46 causes shaft 41 to turn through 30° in a counterclockwise direction. Next, cam 88 causes contact 90 to open the short circuit across resistor 151.

45

Consequently, the field winding 40 is energized only by current reaching it via said resistor over the preenergizing circuit for that winding, and the resultant drop in magnetization of pole piece 34 permits shaft 41 to rotate an additional 30° in a counterclockwise direction (due to the attraction of rotor element 46 by pole piece 33, which still is strongly magnetized).

50

Next, contact 91 short-circuits resistor 149, increasing the energization of winding 38; then contact 92 opens the short circuit across resistor 150, reducing the current flow through winding 39. At each of these times it will be

55

apparent that shaft 41 rotates an additional 30° , the operation being set forth more in detail in the following table, which shows the status of the field coils and shaft of the three-gang motor at the end of each successive 60° rotation of the

75

cam 88 throughout the first three complete revolutions of said cam:

Position of cam 88 relative to its Fig. 16 position	Field coils which are completely energized	Position of shaft 41 relative to its Fig. 16 position
0°		0°
60° counterclockwise	39 and 40	30° counterclockwise.
120° counterclockwise	39	60° counterclockwise.
180° counterclockwise	38 and 39	90° counterclockwise.
240° counterclockwise	38	120° counterclockwise.
300° counterclockwise	38 and	150° counterclockwise.
360° counterclockwise	40	180° counterclockwise.
420° counterclockwise	39 and 40	210° counterclockwise.
480° counterclockwise	39	240° counterclockwise.
540° counterclockwise	38 and 39	270° counterclockwise.
600° counterclockwise	38	300° counterclockwise.
660° counterclockwise	38 and	330° counterclockwise.
720° counterclockwise	40	360° counterclockwise.
780° counterclockwise	39 and 40	390° counterclockwise.
840° counterclockwise	39	420° counterclockwise.
900° counterclockwise	38 and 39	450° counterclockwise.
960° counterclockwise	38	480° counterclockwise.
1,020° counterclockwise	38 and	510° counterclockwise.
1,080° counterclockwise	40	540° counterclockwise.

From the above it will be seen that the three element motor functions the same general way that it did when the antenna was being unreeled; however, because cam 88 now is turning in a counterclockwise direction, the field coils 38, 39 and 40 become active (i. e., completely energized) in the reverse sequence, causing shaft 41 to turn in a counterclockwise direction, instead of clockwise as it did during unreeling. Accordingly, the reading of counter 50 decreases with each revolution of the reel until it finally reaches "000." Simultaneously, the "fish" 126 enters the mouth of the fairlead 139, and, being unable to advance into the constricted throat thereof, prevents the reel from rotating further. This halts the worm wheel 119, the cam 88 and shaft 41 of the three-gang motor. Worm wheel 119, now being maintained stationary, acts as a rack for the rotating worm, so that the latter screws itself to the right along shaft 114, moving the "in limit" disc 123 against the force of spring 124. The "in limit" disc soon engages lever 133, and turns it in a counterclockwise direction, opening contact 86. This interrupts the circuit for the clutch magnet 111 whereupon rotation of the worm is quickly stopped. It also opens the circuit for motor 102; for the field coils of the three element motor; and for the lamp 58.

The operator, seeing that lamp 58 no longer is lighted, knows that the antenna is completely retracted and that the mechanism has come to rest with each part occupying the position it occupied before the antenna was unreeled. He may now restore switch 60 to normal, although no harm will be done if he leaves the switch thrown to its "in" position until he again wishes to reel out the antenna. In any event, no change will be produced until switch 60 once more is thrown to its "out" position, at which time the reeling-out process will again start, as already described.

It will be clear that the operator can, if he so desires, stop the reeling-in process at any time before the antenna is wholly retracted. To do this he simply restores switch 60 to normal, which interrupts the clutch circuit at contact 159 and interrupts the motor circuit at contact 156, thus halting the reel. Moreover, having stopped the reel with the antenna still partially extended, he may thereafter initiate rotation of the reel in whichever direction he chooses, by throwing switch 60 either to its "in" or "out" position. If he does the former, the circuit for motor winding 158 will be completed at contact 156; if he

does the latter, the circuit for motor winding 144 will be completed at contact 149. In either case the clutch will be reoperated (due, in one instance, to the closing of contact 159, and, in the other, to the closing of contacts 140 and 145). Accordingly the operator may make the extended antenna longer or shorter at will, changing its length as many times as he wishes before he causes it to be retracted.

10 Function of the "out limit" disc

If the operator, having thrown switch 60 to its "out" position to start the mechanism to reel out the antenna, should accidentally or intentionally fail to restore said switch to normal before the antenna is entirely unreeled, the mechanism will stop itself in the following way: When the full length of the antenna is unreeled, the innermost end thereof which is securely fastened to the reel will pass bottom dead center, and the drag of the antenna accordingly will exert a force tending to rotate the reel, not in a clockwise direction as before, but in a counterclockwise direction. This tendency of the reel to rotate in a counterclockwise direction is transmitted to the worm wheel 119 which therefore urges the worm to the left on shaft 114. It will be remembered that if the worm wheel remained stationary, the worm would screw itself to the left along shaft 114 due to its own rotation, as pointed out earlier, and accordingly with this sudden encouragement of worm wheel 119 to move in that direction the worm does so. Consequently as the "out limit" disc 122 slides to the left it rotates lever 129 in a clockwise direction, closing contact 85, which thereupon energizes the winding of relay 68 over the following circuit: positive battery, contact 85, conductor 160, relay 68, conductor 148 and negative battery. At contact 69, the relay opens the circuit of motor 102 and also the circuit of the winding 111 for the magnetic clutch, whereupon the mechanism rapidly is brought to a halt in the manner already described.

In the event that the reeling out process is started by throwing switch 60 to its "out" position while the aircraft is on the ground, the mechanism will operate in the usual way until the "fish" 126 comes to rest on the earth. When this happens its weight no longer tends to rotate the reel and worm wheel 119 in a clockwise direction, and accordingly there is a substantial reduction in the force urging the worm 118 to the right on shaft 114. Under this condition the pressure of the light spring 125 (see Fig. 15) urging the worm to the left is sufficient to cause the rotating worm to screw itself along shaft 114 toward gear 116. The "out limit" disc quickly operates the lever 129, closing contact 85 and thereby causing relay 68 to halt the mechanism, as before. Since unreeling stops automatically as soon as the "fish" strikes the ground, the antenna is prevented from becoming tangled.

Similarly, if the antenna should, while unreeling, become snagged on some projecting part of the aircraft, or if the "fish" 126 should become detached from the antenna, there will not be sufficient clockwise rotational pull on the reel to keep the spring 125 compressed. Under such circumstances, as in the cases already described, the spring 125 will cause the rotating worm to move to the left along shaft 114 until the "out limit" disc 122, by closing contact 85, operates relay 68 and thereby halts the mechanism. In fact, it should be clear that if the rotational pull on the reel due to the drag of the antenna and "fish" 126 is reduced materially below its normal value for

any reason, it thereby becomes impossible to operate the motor 102 in such a direction as will unwind the antenna further. (Whenever unreeling stops, the operation of the three-gang motor also stops, as already explained, so that even under abnormal circumstances the counter 56 correctly indicates the number of turns of the antenna which have been unwound.)

Function of the slow acting relay

In most of the cases described in the preceding section it will be noted that the reeling out process was in full swing at the time the "out limit" disc became operative to prevent the antenna from being unreeled further. Whenever such is true, the inertia of reel 71 makes it impossible for the reel to come to rest as quickly as shaft 114 stops rotating. Assuming, then, that the shaft has been halted due to the operation of relay 68 (which, as explained above, is due, in turn, to a sufficient reduction in the antenna's tangential pull to permit the "out limit" disc to move to the left) the tendency of the reel to continue rotating will result in a rotation of the worm wheel 119 in a clockwise direction. This causes the worm and "out limit" disc to slide to the right along shaft 114, first compressing spring 125 and then compressing spring 124. Much of the kinetic energy of the reel is expended in compressing these springs, so that when the "in limit" disc strikes the sleeve 135 the reel is halted without imposing an excessive strain upon any of the parts. Since the reel now is stationary it will be apparent that the springs will at once return the two limit discs to their respective extreme left-hand positions on shaft 114 (it being remembered that, under the condition assumed, the antenna is not exerting sufficient force on the reel to maintain spring 125 compressed).

From these facts it will be clear that after relay 68 has operated and caused shaft 114 to halt, its circuit frequently is interrupted at contact 85 for a brief interval, as a result of the reel momentarily sliding the "out limit" disc to the right. During this interval the relay remains operated due to its slug, and hence maintains the contact 69 open.

The relay's ability to absorb this momentary circuit interruption is of considerable importance, for if it failed to do so the circuit for windings 111 and 144 would be re-established at contact 69 as soon as contact 85 opened. This would cause shaft 114 to resume its rotation, giving fresh impetus to the rotation of reel 71 and causing the worm to slide back to the left on shaft 114. As a result of the latter movement, the "out limit" disc would again close contact 85, thereby operating relay 68 and bringing shaft 114 again to a halt. No sooner would shaft 114 be halted than would the reel, due to its continued rotation, once more cause the worm and "out limit" disc to slide back to the right on the shaft. This, by opening contact 85, would again release relay 68, thereby re-establishing the circuits for the motor and clutch with the result that shaft 114 would again resume its rotation, beginning another cycle substantially identical to the first. An undesirable mode of operation such as this has been found capable of sustaining itself through a sufficient number of successive cycles like the one indicated to defeat the purpose of the apparatus.

Relay 68 successfully prevents this manner of operation by maintaining contact 69 open despite the transitory interruption of its circuit at contact 85. In this way the reel is brought to a swift, sure

halt, whereas it otherwise would be alternately accelerated and decelerated over a prolonged period, coming to a stop in a jerky, stuttering fashion which would not only impose considerable stress on the mechanism but would unreel additional antenna contrary to the purpose of the arrangement.

It will be observed that contacts 69 and 140 in series are shunted by a condenser 161 which, in the well known way, absorbs any inductive surge occurring when either of these contacts is opened, thereby preventing the surge from creating an arc at the open contact. Likewise, contacts 86 and 156 in series are shunted by a condenser 162 which in the same way eliminates arcing at either of the latter contacts.

Having described the invention, what is considered new and is desired to be protected by Letters Patent is set forth in the following claims.

- 10 20. What is claimed is:
  1. In an arrangement of the kind described, an antenna occupying a certain position, a mechanism operative to move said antenna away from said certain position and through a plurality of successive intermediate positions to another position, an electrical circuit, means controlled by said mechanism for preparing said circuit just prior to said movement, and other means then controlled by said mechanism over said circuit for registering, at substantially every instant during the time that said antenna is moving from said certain position to said other position, the amount by which the position of said antenna has been changed at that instant.
  2. In combination, a first member and a second member linked by a yieldable coupling, a motor associated with said first member for driving said first member and hence driving said second member via said coupling, a circuit for starting and stopping the driving of said first member by said motor, thereby to start and stop said second member, each of said members effective to subject said coupling to varying forces in accordance with changes in the motion of that member, said coupling effective to yield in the presence of a certain degree of unbalance in the forces to which it is subjected by said two members, a circuit, means governed by the yielding of said coupling for controlling said last circuit, and a slow relay in said last circuit operated responsive only to a prolonged control of that circuit by said last means for altering said first circuit.
  3. In combination, a first movable member, a motor for moving said member, a circuit for controlling the movement of said member by said motor, a yieldable coupling, a second movable member linked to said first member via said coupling, whereby said first member causes said second member to be moved at a speed varying in accordance with the speed of said first member, each of said members effective to subject said coupling to forces varying in accordance with the variations in rate of change of the speed of that member, said coupling effective to yield in the presence of a certain degree of unbalance in the forces to which it is subjected by said two members, a circuit, means governed by the yielding of said coupling for controlling said last circuit, and a slow relay in said last circuit operated responsive only to a prolonged control of that circuit by said last means for altering said first circuit.
  4. In an extensible antenna control system, a rotatable antenna reel, a mechanism for rotating said reel in either direction thereby to extend or retract the antenna, a source of current, a plu-
- 25 30 35 40 45 50 55 60 65 70

rality of circuits, means controlled by said mechanism for establishing a flow of current from said source over said circuits just prior to the extension of said antenna from a retracted position, a cam mechanically coupled to said reel and hence rotated throughout said extension of the antenna, contact means controlled by said cam when thus rotated for influencing the flow of current in said circuits sequentially, and register means under the joint control of said circuits operated progressively during the extension of said antenna due to said influencing of the current flow in said circuits.

5. In an extensible antenna control system, a rotatable antenna reel, a mechanism for rotating said reel in either direction thereby to extend or retract the antenna, a source of current, a plurality of circuits over which current from said source flows whenever said antenna is in an extended condition, register means under the joint control of said circuits, a cam mechanically coupled to said reel and hence rotated whenever the reel is rotated, contact means controlled by said cam for influencing the flow of current in said circuits sequentially whenever said cam is rotated, thereby to operate said register means progressively throughout such rotation of said cam, and means operated responsive to the antenna reaching its fully retracted position for interrupting the flow of current over said circuits.

6. In an arrangement of the kind described, an antenna occupying a certain position, a register, a source of current for said register, means for preventing current from flowing from said source

to said register so long as said antenna remains in said position, a mechanism for moving said antenna away from said position, and means controlled by said mechanism independently of said antenna for causing a flow of current from said source to operate said register progressively throughout said movement of the antenna by said mechanism.

7. In an arrangement of the kind described, a movable antenna, a register, a source of electrical current for said register, means for operating said register from said source under control of said mechanism thereby to change the registration progressively throughout the movement of said antenna, and means controlled by said mechanism at the end of said movement for terminating the flow of current from said source to said register.

8. In a mechanism of the kind described, a movable antenna having a normal position, mechanism for moving said antenna, means operated when said antenna is at normal for initiating the operation of said mechanism, delay means in said mechanism whereby said mechanism begins to move said antenna away from normal a brief interval after the operation of said first means, a motor, means controlled by said delay means during said interval for preparing an electric circuit for said motor, means then controlled by said mechanism upon initiation of the movement of said antenna for starting to operate said motor over said circuit, and a register driven by said motor upon the latter's operation.

EDWARD S. PETERSON.
